UNITED STATES PATENT OFFICE.

JULIUS L. FRITZ, OF PHILADELPHIA, PENNSYLVANIA, ASSIGNOR, BY DIRECT AND MESNE ASSIGNMENTS, TO FRITZ CARBURETOR COMPANY, OF NORRISTOWN, PENNSYLVANIA, A CORPORATION OF PENNSYLVANIA.

AUTOMATIC PRIMING DEVICE FOR CARBURETERS.

1,181,128.

Specification of Letters Patent.

Patented May 2, 1916.

Application filed June 7, 1913. Serial No. 772,273.

To all whom it may concern:

Be it known that I, JULIUS L. FRITZ, a citizen of the United States, residing in the city and county of Philadelphia, State of Pennsylvania, have invented a new and useful Automatic Priming Device for Carbureters, of which the following is a specification.

My present invention consists of an automatic priming device, which is designed to be located between the carbureter and the intake manifold of an internal combustion engine, and although the same is adapted to be employed in conjunction with any desired or conventional type of carbureter, I have preferred to illustrate the same as employed in conjunction with a carbureter corresponding to my prior Patent No. 993,770, patented May 30th, 1911.

In one of my prior Patents No. 1,048,518, patented December 31st, 1912, and reissued June 24, 1913, Serial No. 13,580, I have described and broadly claimed a novel construction of an automatic priming device, wherein novel means are provided for introducing additional fuel into the intake leading to the manifold, and novel means for controlling the admission of such additional fuel, and although the same has been found in practice to give marked and advantageous results, it has been found that under certain conditions arising in practice there is a liability of a leakage of fuel around the valve into the passage leading to the intake manifold of the internal combustion engine, since the vacuum in the by-pass does not always become broken.

With the above in view, my present invention consists of a novel construction of an automatic priming device, whereby at the desired time fuel is projected into the engine automatically through a by-pass leading from the source of fuel supply, such as, for example, the float chamber of the carbureter and wherein means are provided for positively breaking the vacuum in such by-pass and thereby prevent any possibility of any fuel passing through said by-pass when the proper steps have been taken to close the same.

It further consists of a valve mechanism, and means for adjusting the same to maintain a substantially constant pressure on the fuel in the by-pass.

It further consists of a priming device 55 wherein means are provided for controlling the passage of fuel and air into the manifold when it is desired to start the engine and novel means for placing air pressure on the fuel when desired. 60

In conjunction with my present invention, I employ a counter-balanced valve corresponding to that disclosed in my prior Patent No. 993,770, which is adapted to be opened by the suction of the engine, novel 65 means being provided for limiting the movement of said valve and for securing said valve in its open position at which time the supply of fuel is automatically cut down so that a compensating mixture is 70 continually maintained in accordance with the speed of the engine.

In carbureters as heretofore constructed, considerable difficulty has arisen, especially in extreme cold weather, in starting an internal combustion engine, such as, for example, the types employed in conjunction with motor vehicles, and although in some instances, it has been proposed to employ a by-pass for admitting an additional supply 75 of fuel to the manifold, the desired results have not been obtained, since proper mechanism has not been provided to automatically control the requisite amount of explosive mixture at the proper time. 85

My invention further consists of other novel features of construction, all as will be hereinafter fully set forth.

For the purpose of illustrating my invention, I have shown in the accompanying 90 drawings one form thereof which is at present preferred by me, since the same has been found in practice to give satisfactory and reliable results, although it is to be understood that the various instrumentalities 95 of which my invention consists can be variously arranged and organized and that my invention is not limited to the precise arrangement and organization of these instrumentalities as herein shown and described. 100

Figure 1 represents a side elevation of a carbureter having a priming device embodying my invention in conjunction therewith. Fig. 2 represents a vertical section of a portion of Fig. 1. Fig. 3 represents a plan view partly broken of a portion of Fig. 1, showing the parts in one position. Fig. 105

4 represents a sectional view of Fig. 3. Fig. 5 represents a plan view corresponding to Fig. 3, but showing the parts in a different relation to each other. Fig. 6 represents a 5 sectional elevation of Fig. 5. Fig. 7 represents a sectional plan view of Fig. 3. Fig. 8 represents a sectional plan view of Fig. 5. Fig. 9 represents a perspective view of a 10 valve embodying my invention. Fig. 10 represents a sectional view of a portion of Fig. 1.

Similar numerals of reference indicate corresponding parts in the figures.

Referring to the drawings: since the carbureter illustrated corresponds to that disclosed in my prior Patent No. 993,770, and since large numbers thereof have been on the market and in successful use for some time, and the construction and operation thereof 15 is well known to those skilled in this art, I have deemed it unnecessary to illustrate and describe in detail the construction and operation of the carbureter *per se*, it being understood that the carbureter 1 is provided 20 with a float chamber 2, from which leads a passage or by-pass 3, preferably formed in the casing of the carbureter. The passage or by-pass 3 is provided with a port 4, which is controlled by means of a valve 5, said 25 valve being rotatably mounted as illustrated in the casing 1 and passing, in the present instance, through the passage 6 which leads to the intake manifold of an internal combustion engine, said passage 6 being provided 30 with a throttle valve 7 which is constructed and operated in the usual and well known manner. This throttle valve 7 I have illustrated as being located anterior to the valve 5, although in practice the same may 35 be placed posterior thereto, if desired. The port 4 is adapted to register with a port 8 in the valve 5, as will be understood by reference to Figs. 6 and 7, said port 8 communicating with a discharge port 9 of the 40 valve 5. The valve 5 at one end is provided with an enlargement 10, having a conical face 11, which is adapted to engage a seat 12 in the casing 1, in order to limit the 45 longitudinal movement of the valve 5 in one direction, so that the port 8 will register with the port 4 at the proper time. The valve 5 has the end opposite the enlargement 10 preferably of a polygonal contour, and in the present instance the same is 50 shown as being faced off, as at 13, in order to receive a locking washer 14, which has a portion deflected to form lugs adapted to engage a seat 15 in a faced off portion of the casing 1, whereby improper movement or 55 accidental displacement of the valve 5 is 60 prevented.

16 designates a spring serving as a tension device for the locking washer 14 and interposed between said washer and an arm 17, 65 which latter is fixed on the end of the valve

5 in any desired manner, it being understood that the arm 17 is adapted to be supplied with a connection extending to a position accessible to the operator such, as for example, the driver of an automobile, in order 70 that said valve 5 may be manually actuated when desired.

18 designates a compensating or controlling valve which is provided with the apertured ears 19 through which the valve 5 passes and on which it is loosely mounted. One side of the valve 18 is counterbalanced or weighted, as indicated at 20, in Fig. 2, and the movement of this valve is limited in any desired manner, and in the present 80 instance I provide a pin or lug 21 which serves normally to maintain the valve 18 in such a position that the passage 6 is closed. The valve 18 is recessed on its upper face as indicated at 22, in order that the arm 23 and fastening device 24 will not interfere with the proper opening of the valve 18. The valve 18 is also provided with apertures 25 therethrough, in order to unbalance the same and equalize the pressure on opposite sides thereof, so that the valve will open 85 more readily due to the suction of the engine.

In order to positively prevent any leaking of fuel from the by-pass 3 into the passage 6, when the valve 5 is in closed position, such as might possibly otherwise occur when the port 8 is out of register with the port 4, I have devised means to create a pressure on the fuel in the by-pass 3 and for convenience of illustration, I have shown one manner of accomplishing this result by forming a groove or slot 26 in the side of the enlargement 10 of the valve 5 and extending through the end thereof so that 90 when the port 8 is brought out of register with the port 4, thereby cutting off the by-pass 3, and the groove or recess 26 brought into register with the port 4, a constant pressure, or as shown, atmospheric pressure 95 will be exerted on the fuel in the by-pass 3 and thereby break the vacuum which was 100 formed therein due to the engine suction.

The operation of my priming device will now be readily understood by those skilled 115 in the art to which this invention appertains and is as follows: The arm 17 is manually actuated to bring the port 8 into register with the port 4, so that upon the turning over of the engine, the engine suction will 120 create a vacuum in the by-pass 3 and cause fuel to pass from the float chamber 2 to said by-pass directly into the passage 6 and thence into the engine cylinders so that an explosive mixture is at once produced therein 125 to enable the engine to start. The engine suction also causes the valve 18 to open thereby permitting the requisite amount of air to pass through the passage 6, in the usual manner and if the valve 18 is moved 130

to its wide open position as seen in Fig. 2 then it will close either wholly or in part the port 9 and thus automatically cut down the supply of additional fuel entering through the by-pass 3 and a compensating mixture of fuel and air is thus constantly maintained in accordance with the speed of the engine, it being seen that a limiting pin 27 is provided as seen in Fig. 2. It will now be understood that the counterbalanced valve 18 is automatically controlled by the engine suction, and on a predetermined increase of the engine suction such valve opens with respect to the passage 6 and closes wholly or in part the port 9 and thus controls automatically the passage of additional fuel from the float chamber 2 to the passage 6.

It has been found in practice that when the valve 5 is turned to bring the port 8 out of register with the port 4 the additional fuel is liable to leak around the valve into the passage 6, with a consequent increase in the consumption of fuel, since the vacuum in the by-pass 3 is not broken and I have found it to give marked and advantageous results in practice by providing means to break the vacuum in the passage 3 and special attention is directed to this basic feature of my invention. By creating a pressure on the fuel in the by-pass 3 such as for example by admitting air thereto, the vacuum is positively broken and any possibility of fuel feeding from the by-pass 3 into the passage 6 is positively prevented. It will be apparent that upon the proper actuation of the arm 17, the valve 5 will be rotated, thereby causing the arm 23 to engage the valve 18 and lock the same in its open or inoperative position. The position of the valve 5 is visibly indicated by the position of the locking washer 14 or by the position of the arm 17 or by the position of the port 26.

It will now be apparent that I have devised an automatic priming device for carbureters, which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a priming device, a carbureter having a fuel supply and a passage leading to an internal combustion engine and a by-pass communicating with said fuel supply and said passage, a manually controlled valve

controlling said by-pass, an engine controlled valve controlling said passage and automatically reducing on a predetermined increase in engine suction the amount of fuel delivered from said by-pass, and means to introduce air into said by-pass to prevent fuel passing therethrough.

2. In an automatic priming device, a carbureter having a fuel supply, and a conduit leading therefrom to a passage leading to the intake manifold of an internal combustion engine, a valve controlling passage of fuel through said conduit, devices controlling passes of fluid through said passage adapted to be opened by the engine suction and to automatically close said conduit on a predetermined increase of the suction, the amount of opening of said devices proportionately varying the amount of fuel passing from the fuel supply to said passage, and means to break the vacuum in said conduit formed by the engine suction.

3. In an automatic priming device, the combination with a carbureter having a float chamber and a passage leading to the intake manifold of an internal combustion engine, of a conduit communicating with said chamber and said passage, a valve controlling said conduit, a second valve controlled by the engine suction and controlling the passage of fuel through said conduit and adapted to close said conduit on a predetermined increase of the engine suction, and means to admit air to said conduit to prevent passage of fuel therethrough.

4. In an automatic priming device, the combination with a carbureter having a float chamber and a passage leading to the intake manifold of an internal combustion engine, of a conduit communicating with said chamber and said passage, a valve controlling said conduit, and a second valve controlling the passage of fuel through said conduit and adapted to be opened with respect to said passage and to be closed with respect to said conduit by the engine suction and to automatically close with respect to said passage when said suction ceases, devices for limiting the movement of said second valve, and means to admit air to said conduit at a desired time to prevent passage of fuel therethrough.

5. In an automatic priming device, the combination with a carbureter having a float chamber and a passage leading to the intake manifold of an internal combustion engine, of a conduit communicating with said chamber and said passage, a valve controlling said conduit, a second valve controlling the passage of fuel through said conduit and adapted to be opened with respect to said passage by the engine suction and to automatically close with respect to said passage when said suction ceases and close with respect to said conduit at a pre

determined increase of the suction, means for rendering the first valve inoperative, and means to create a pressure in said conduit to prevent passage of fuel therethrough.

5 6. In an automatic priming device, the combination with a carbureter having a float chamber and a passage leading to the intake manifold of an internal combustion engine, of a conduit communicating with said chamber and said passage, a valve controlling said conduit, a second valve controlling said conduit and adapted to be opened by the engine suction and to automatically close said passage when said suction ceases and to close 10 said conduit at a predetermined increase of the suction, means for rendering the second valve inoperative, and means to create a pressure in said by-pass to prevent passage 15 of fuel therethrough.

20 7. In an automatic priming device, the combination with a carbureter having a float chamber and a passage leading to the intake manifold of an internal combustion engine, of a conduit communicating with said chamber and said passage, a valve controlling said conduit, a counterbalanced valve loosely mounted on said first valve and controlling passage of fuel therethrough, and means to admit air to said by-pass to prevent passage 25 of fuel therethrough.

25 8. In an automatic priming device, the combination with a carbureter having a float chamber and a passage leading to the intake manifold of an internal combustion engine, of a conduit communicating with said chamber and said passage, a valve controlling said conduit, a compensating valve loosely mounted on said first valve and counterbalanced to provide for the automatic closing 30

of the same with respect to said passage, said compensating valve varying the amount of fuel passing through said first valve and also controlling admission of air to said passage and means to admit air to said conduit to prevent passage of fuel therethrough. 40

9. In an automatic priming device, in combination with a carbureter having a float chamber and a passage leading to the intake of an internal combustion chamber, of a by-pass communicating with the float chamber and said passage, a counterbalanced valve rotatably mounted and adapted to vary the amount of fuel entering said passage, devices for rendering said counterbalanced valve inoperative, and means to admit air to said by-pass to prevent passage of fuel therethrough. 45

10. In an automatic priming device, a carbureter having a discharge passage and a fuel supply and a by-pass communicating with said passage and fuel supply, a valve controlling passage of fuel through said by-pass and admission of air into said by-pass, and a second valve controlled by the engine suction and controlling passage of fuel from 50 the first valve into said discharge passage. 60

11. In an automatic priming device, a carbureter having a by-pass communicating with the fuel supply and with the intake manifold of the engine, means controlled 70 by the engine suction to control said by-pass, and means to place a pressure on the fuel in said by-pass to prevent its feed therethrough.
